BRAKE LEVER CONSTRUCTION

Herbert S. Jandus, Detroit, Mich., and Ray A. Sandberg, Waukegan, Ill., assignors, by mesne assignments, to Houdaille-Hershey Corporation, Detroit, Mich., a corporation of Michigan

Application April 3, 1937, Serial No. 134,702

8 Claims. (Cl. 74—537)

The present invention relates to brake lever construction and more particularly to means for closing the free end of a lever without applying a cap to such end. In the manufacture of 5 brake levers from sheet material by stamping and like operations, the matter of closing or capping the free ends of the levers, that is, the free ends of the grip portions of the levers, amounts to appreciable items of expense as additional manufacturing operations are necessary.

It is desirable to close the extremities of the free ends of such levers to protect the operators from injury to their hands in manipulating the levers.

15 The present invention provides closure means for the ends of stamped levers which closure means may be economically manufactured and which serve to fully protect the operator's hands from injury when operating the levers.

20 An object of the present invention is to provide novel means for closing the open, free ends of brake levers which are fashioned from sheet material.

25 Another object of the present invention is to provide a novel closure for the open, free end of a hollow tubular or channel shaped brake lever, which closure is economical to manufacture and efficient for the purpose intended.

30 A further object of the present invention is to provide a protective covering for the open end of a formed brake lever which covering effectually protects the operator's hand from injury.

35 Generally speaking the invention contemplates the provision of a clutch or latch release actuating member provided with a part adapted to normally overlie the free end of the grip portion of a lever.

40 The above other and further objects of the present invention will be clearly apparent from the following description and accompanying drawing.

45 The accompanying drawing illustrates embodiments of the present invention and the views thereof are as follows:

Figure 1 is an elevational edge view of a brake lever constructed in accordance with the principles of the present invention and showing the parts of the lever in "off" position.

50 Figure 2 is a view, partially in longitudinal section and partially in elevation of the lever of Figure 1 showing the relationship of the parts with the lever in "off" position and the latch actuating member in normal position closing the open free end of the lever.

55 Figure 3 is a fragmental view, partially in sec-

tion and partially in elevation of the upper end of the lever of Figure 2 showing the part with the lever in "set" position.

Figure 4 is a fragmental view, partially in longitudinal section and partially in elevation, of another form of the present invention.

Figure 5 is an enlarged transverse sectional view taken substantially in the plane indicated by line V—V of Figure 2.

Figure 6 is an enlarged transverse sectional view taken substantially in the plane indicated by line VI—VI of Figure 4.

Figure 7 is a view, partially in elevation and partially in central section, of fragmental portions of a brake lever showing a still further modification of the present invention, with approximately half of the actuating member illustrated.

The drawing will now be explained.

The brake lever chosen to exemplify the present invention has been illustrated as utilizing a swinging sector or ratchet. It is to be understood that the invention is capable of application to a lever of other forms than that shown, for example, a form having a fixed ratchet.

The lever herein illustrated is of the dash type and includes a supporting plate 1 adapted, in the well known manner, for attachment to an automotive vehicle behind the instrument board.

The lever is of stamped metal formed as channel or U-shaped for a major portion of its length with a web 2 and side walls 3 and 4 which at the upper end of the lever become parallel legs 5 and 6 for pivotal attachment, as by means of a suitable pin 7 to the plate 1.

Pivoted at 8 to the legs of the lever is a swinging or oscillating ratchet member 9 having a series of ratchet teeth 10 formed in an arcuate portion of its margin. Links 11 connected at similar ends to the plate 1 as by a pivot or pin 12 and at the opposite ends by means of a suitable pivot 13 to the ratchet member 9, cause the member to oscillate about its pivot 8 as the lever is swung in use to move the ratchet teeth 10 with respect to the point engaging part of a pawl.

A pawl 14 is pivoted to the lever by means of a tubular pivot 15, and at one end has a point 16 for making latching engagement with any one of the teeth of the ratchet 10 of the element 17 or member 9.

A latch release member, preferably of channel or U-shape throughout the major portion of its length, and formed with a web 17 and side walls 18 and 19 is pivotally connected at its upper end

to the pawl member 14 by means of a suitable pivot 20. As illustrated the latch release member 17 is arranged in assembled relation with respect to the lever so that the walls of the latch release member work within the side walls of the lever.

A pawl actuating member indicated generally as A is fashioned from flat sheet metal to provide a structure which, in elevation, is substantially L-shaped and in transverse section, is channel or U-shaped. As formed the pawl actuating member A has a grip portion 21 which extends generally in the direction of the length of the lever from its free end toward its pivoted end and lies along the grip portion of the lever. The side walls of an angular part of the actuating member A designated at 22 and 23 are laterally spaced and work within the side walls of the lever adjacent the free end of the lever. These walls 22 and 23 are pivotally attached as by means of a suitable pivot 24 to the lever, closely adjacent its free end, so that the pawl actuating member A may rock about the pivot 24 in use.

The lower end of the latch release member 17 is pivoted at 25 to the pawl actuating member A, in the neighborhood of the angle between the arms of this member.

In order to maintain the latch release member 17, the pawl actuating member A in one position, and the pawl in latched engagement with the ratchet member 9, spring means are utilized.

The form of spring illustrated is secured at one end 26 to a portion of the lever, the end being shown as passing through an opening 27 in the web of the lever and its other end 28 is hooked through an opening 29 in the web of the latch release member 17. This spring is a tension spring and normally maintains the parts with the pawl in latched engagement with its ratchet so as to hold the lever in adjusted position.

The form of lever construction shown in Figures 2 and 3 is that in which the pawl pivot lies between its ratchet engaging point 16 and its point of connection to the latch release member 17.

Fig. 4 illustrates another form of the invention wherein the pawl 30 is pivoted to the lever by means of a hollow tubular pivot 31 at one end of the pawl, the other end of the pawl being provided with a point 32 for effecting latching engagement with the ratchet.

In this form of invention, the actuating member A' is pivoted at 33 to ears 34, 35 which project from the walls 36 and 37 respectively of this form of lever, adjacent the free end of the lever.

This actuating member A' is substantially right-angular in side elevation and with a portion extending within the channel of the grip portion of the lever where pivotal connection is made at 38 with a latch release member 39. The other end of the latch release member 39 is pivoted at 40 to the pawl 30.

In this form of the invention, a spring 41 is connected between the lever and the latch release member in such manner as to normally maintain the pawl in latched engagement with its ratchet.

The lower end of the grip portion of the lever of Fig. 2 is embossed at 42, while the lower end of the lever of Fig. 4 is embossed at 43 to provide bulges at the free ends of the levers for the operator's hands when grasping the levers to operate them.

It will be observed that the free ends of the levers of Figs. 2 and 4 are open.

In order to provide closures for the free ends of the levers, the actuating member A is provided with a part 43 which normally closes the extremity of the free end of the lever 2 of Fig. 2.

The actuating member A' of Fig. 4 is likewise provided with a part 44 which normally closes the open free end of the lever of this form.

Figs. 2 and 4 show the actuating members A and A' respectively in normal position, with the parts 43 and 44 forming covers or closures for the open extremities of the free ends of the levers.

The form of the invention illustrated in Fig. 7 includes an angularly shaped actuating member A^{III} made from sheet metal stock. The portion 15 of the actuating member A^{III} which overlies the free end of the extremity of the lever is cup shaped as at 48. Secured to the interior of the cup shaped portion of the actuating member is a strap 49 which has the adjacent end of the latch release member 50 secured to it as for example by having the extremity of the member 50 pass through an opening in the strap and headed at 51. Sufficient play between the strap 49 and the release member 50 is permitted to prevent the parts from binding in use. In this form of the invention, the latch release member 50 is attached to the strap 49 and the strap 49 is then secured to the interior of the cup 48 of the actuating member A^{III} as by welding or any other suitable 30 method, whereupon the parts are assembled, the upper end of the latch member 50 is attached to its pawl and then the actuating member A^{III} is secured by its pivot 47 in operative position.

It will be observed that the form of the invention illustrated in Figure 7 shows an actuating member formed as a stamping, which is angular in side elevation and channel shape in cross section or profile. The actuating member is so arranged with respect to the open end of the grip portion of the lever member that the open end is concealed at all times and that the actuating member is shaped to surround the open end of the grip portion of the lever for a distance of at least approximately one-half of the peripheral extent of said end.

The release rod 50 instead of being connected to the actuating member A^{III} as shown in Figure 7, might be pivotally connected to it in the manner suggested and shown in the forms of the invention illustrated in Figures 2 and 4.

It will be observed that the present invention provides a pawl actuating member which at the same time forms a closure or cover for the extremity of the free end of the lever, making unnecessary the capping operation heretofore requisite in connection with the manufacture of formed or capped levers.

The actuating members may be readily manufactured from flat sheet material, by stamping 60 or like processes, providing the grip portions, the attaching legs and the closure members for the extremities of the levers, without appreciable waste, thereby reducing cost of manufacture of such levers.

In the commercial field, such levers are sold on competitive basis so that any economy of manufacture which may be effected is reflected in lower prices to the consumer and increased profits to the manufacturer.

In the operation of the present invention, when it is desired to move a lever from "off" position to "set" position, the operator grasps the grip portion of the lever which is the lower portion as shown in the drawing and swings it in counter-

clockwise direction as viewed in Figs. 2, 3 and 4. During such application of the brake, the operator may or may not press the grip portion of the actuating member toward the grip portion of the lever. In any event the brake may be set as by swinging the lever the pawl travels along the ratchet and the ratchet is given rocking movement about its pivot in a direction to advance the ratchet teeth with respect to the pawl point and thus finer adjustment of the brake is setting it.

To release the brake, the operator presses the grip portion of the actuating member toward the grip portion of the lever whereupon the pawl is unlatched from its ratchet and the lever returned to "off" position, the operator, of course, during this movement maintaining squeezing pressure on the grip portions of the actuating member and lever. As soon as he releases his gripping pressure the spring becomes effective to return the actuating member to normal position and to cause latching engagement of the pawl with its ratchet.

It will be observed that the construction of the present invention very readily provides a closure for the free end of a lever of such nature as to at all times protect the operator against injury which might otherwise be occasioned if the free end of the lever were not closed.

The reason for closing the free ends of the levers is to prevent injury to the operator, as sometimes there is a possibility of the free ends of the levers having slightly roughened parts which might scratch the hand of an operator or be the cause for his tearing some portion of his clothing on the levers. With the free ends closed or covered as contemplated by the present invention, all such hazards are eliminated.

The invention has been described herein more or less precisely as to details, yet it is to be understood that the invention is not to be limited thereby, as changes may be made in the arrangement and proportion of parts, and equivalents may be substituted, without departing from the spirit and scope of the invention.

The invention is claimed as follows:

1. An emergency brake lever construction for automotive vehicles including a stamping comprising a lever member having hollow shank and grip portions with the extremity of the grip portion open, a pawl release member working within the hollow shank and grip portions, means cooperating with said release member to latch and unlatch said lever member, spring means normally maintaining said release member in one position, and a stamping comprising an actuating member angular in side elevation and of channel shape in cross section pivoted to said lever member closely adjacent the open end of said grip portion and having a pawl engaging manipulating part extending along the grip portion of said lever member and having another part extending substantially transversely of the lever member and constituting a closure for the said open end of said grip portion, and said release member being operably connected to said actuating member inwardly of said another part of said actuating member.

2. An emergency brake lever construction for automotive vehicles including a stamping comprising a lever member having hollow shank and grip portions with the free end extremity of the grip portion open and unfinished, a pawl release member working within the hollow shank and grip portions, means cooperating with said release

member to latch and unlatch said lever member, spring means normally maintaining said release member in one position and a stamping comprising an actuating member angular in side elevation and of channel shape in cross section pivoted to said lever member closely adjacent the open end of said grip portion and having a manipulating part extending along the grip portion of said lever member and having another part extending substantially across the open end of said lever member and constituting a closure for said end and positioned to conceal said open end and to prevent injury to a hand of an operator while manipulating said actuating member and lever member, said release member being operably connected to said actuating member inwardly of said another part of said latter member.

3. In combination, an automotive vehicle emergency brake lever comprising a member having a hollow grip portion which is open at its free end, a pawl release member working within said grip portion, and an actuating member pivoted to said lever member closely adjacent the open end of said grip portion and having a manipulating part extending along said grip portion and having an angular part extending across said open end and constituting a closure for said open end, said release member being positively connected to said actuating member in such manner that the connection is concealed from view by said angular part.

4. In combination, an automotive emergency brake lever having a grip portion formed with its free end open and unfinished, clutch means operative through said grip portion of said lever member, and a stamping comprising an actuating member angular in side elevation and of channel shape in cross section pivoted to said lever member closely adjacent the open end of said grip portion of said lever member and shaped to peripherally surround the grip portion adjacent said open end for a distance at least 180° of the peripheral extent of said end.

5. In combination with an automotive vehicle emergency brake lever having a grip portion formed with its free end open, of a stamping comprising an actuating member angular in side elevation and of channel shape in cross section which channel is closed at one end, said member being pivoted to the lever member adjacent said open end and arranged with one end of said actuating member overlying said open end and the channel walls of said one end peripherally encompassing at least substantially half the peripheral extent of said open end to thereby conceal said end as said member is rocked.

6. An emergency brake lever for automotive vehicles including a lever member having a hollow interior and with the end of the grip extremity open and unfinished, a latch release member working within the hollow of said lever member and urged to one position by resilient return means, and an actuating member for said release member of angular form in side elevation pivoted to said lever member closely adjacent said open end and having a manipulating part lying along the grip portion of said lever member and having another part projecting across said open end and in concealing and protecting position and laterally encompassing a portion of the periphery of said open end.

7. A mechanism control comprising in combination, a support, a lever member formed to substantially U-shaped cross section throughout its length and including a grip portion at one end

- and being pivoted at the other end to said support, cooperating clutching members having cooperating clutching surfaces to hold said lever member in adjusted position, a clutch releasing member actuator comprising a stamping angular in side elevation and pivoted to said lever member closely adjacent the extremity of the grip portion and having a palm engaging part extending along the grip portion of the lever member 5 and overlying and concealing the slot of the grip portion and having another part extending substantially across and over the open end of said grip portion to constitute a closure for said end, a clutch releasing member operative within the slot of said lever member and connected at one end to said actuator and at the other end connected to one of said clutching members, and spring means for urging said clutching members to clutching position.
5. A mechanism control comprising in combination, a support, a lever member comprising a stamping forming shank and grip portions slotted from end to end of said portions and having spaced legs at one end opposite the grip portion 10
- 10 and overlying and concealing the slot of said grip portion and having another part extending substantially across and over the open end of said grip portion to constitute a closure for said end, a clutch releasing member operative within the slot of said lever member and grip portion and connected at one end to said actuator and at the other end to one of said clutching members, and means acting on said clutch releasing member for urging said 15 clutching members to clutching position.
- 15 20
8. A mechanism control comprising in combination, a support, a lever member comprising a stamping forming shank and grip portions slotted from end to end of said portions and having spaced legs at one end opposite the grip portion
